UNITED STATES PATENT OFFICE.

PLINY E. MEANS, OF TYRONE, NEW MEXICO.

SAFETY ATTACHMENT FOR SYNCHROSCOPES.

1,230,003.

Specification of Letters Patent. Patented June 12, 1917.

Application filed August 6, 1915. Serial No. 44,045.

To all whom it may concern:

Be it known that I, PLINY E. MEANS, a citizen of the United States, residing at Tyrone, in the county of Grant and State 5 of New Mexico, have invented certain new and useful Improvements in Safety Attachments for Synchroscopes; and I do hereby declare the following to be a full, clear, and exact description of the invention, such as 10 will enable others skilled in the art to which it appertains to make and use the same.

This invention relates to new and useful improvements in synchroscopes.

The principal object of the invention is to 15 provide a device which will prevent the cutting in or tying together of two sources of alternating electric current until the same are in proper synchronism.

Another object of the invention is to provide 20 a device which will insure the two generators being in phase before they can be thrown into parallel.

A further object of the invention is to provide 25 a device capable of being readily attached to the ordinary synchroscope without making any material change therein.

Still another object of the invention is to provide 30 a device which will prevent the flow of current into the line until the hand of the synchroscope is in such a position as to indicate that the two generators are in phase.

With the above and other objects in view, the invention consists in the novel combination 35 and arrangement of parts which will be fully set forth in the following specification and accompanying drawings, in which:

Figure 1 is a face view of a synchroscope showing this improved device applied 40 thereto.

Fig. 2 is a fragmentary vertical sectional view through Fig. 1.

Fig. 3 is a horizontal sectional view through Fig. 1.

Fig. 4 is a vertical sectional view of the modified form showing the attachment applied to the back of the synchroscope.

Fig. 5 is a view illustrating a further modified form of the device, and

Fig. 6 is a wiring diagram.

Referring now to the drawings by characters of reference, the numeral 1 designates the casing of the synchroscope having journaled therein the shaft 2. This 55 shaft 2 carries the usual hand 3, which indicates when in its vertical position that

the two generators are in phase. Carried by the shaft and rotatable therewith is a bridging contact 4, which has secured thereto the spring 5 by means of the rivets 60 6, which extend through slots in said spring and into the contact. This spring 5 bears against the inner side of the hand 3 so that the contact 4 is normally held spaced from the hand.

65

Hinged to one side of the casing 1 and extending transversely thereof is the bar 7, provided intermediate its end with the enlargement 8, having the opening 9 formed therein and this enlargement carries a suitable insulating material 10 on which the contacts 11 are mounted. These contacts are arranged to coöperate with the bridging contact 4 in completing the circuit when the hand is in its vertical position. Pivoted 70 as at 12 to the end of the bar 7 opposite the one which is pivoted to the casing 1 is a rod 13, the opposite end of which is connected to the sliding core of the solenoid which will be more fully hereinafter de- 75 scribed.

70

The solenoid is designated generally by the numeral 14 and comprises the coil 15 provided with the sliding core 16, one end of which is connected to the rod 13. A 80 suitable casing 17 surrounds the core and the coil and is provided with an opening 18 through which the rod 13 is slidable. A coil spring 19 bears against the inner face of the casing 17 and against one end of the 90 solenoid core 16 so as to normally hold the core within the coil. A thumb screw 20 is threaded into the end of the core 16 of the solenoid opposite the end to which the rod 13 is connected and bears against the end 95 of the casing. This thumb screw is designed to adjust the movement of the core so as to control the movement of the arm 7.

95

It is to be understood that if so desired the contact 11 may be supported as illustrated in Fig. 5 on suitable springs 21, which may be rigidly attached to the face or to the rear of the casing 1. It is of course to be understood that these springs or contacts are insulated from each other to 100 avoid closing the circuit until the bridging contact 4 engages the same. It is further to be understood that the contact and bridging contact 4 may be placed on the rear of the casing 1 as indicated in Fig. 4 so as 110 to carry the same to a point where it will be out of sight, and also allowing all con-

tacts to be made in the rear of the synchro-
scope. In connection with the operating
lever it will be understood that the same
may be connected in any desired manner to
5 the casing or to any suitable support which
will allow the same to operate in the manner
set forth, in the above.

Upon referring to the wiring diagram,
Fig. 6, it will be seen that the exciting cur-
10 rent is carried over the bus bars A from the
exciter and the cutting in of the A. C. gen-
erators is controlled by the main switches
B and C. These switches being controlled
15 by the solenoids 22 and 23 respectively, and
one terminal of the solenoid 22 is connected
by means of the wire 24 to the contact 25
of the control switch designated by the nu-
meral 26. The contact 27 of the control
20 switch is connected to the wire 28, which
leads to one of the contacts 11 of the syn-
chro-
scope. This contact will be designated
a. The opposite contact 11 of the synchro-
scope is designated by the character b and
is connected to the wire 29 which leads to
25 the terminal of the solenoid 22 opposite the
one to which the wire 24 is connected. The
switch blades 30 and 31 are respectively
pivoted to the contacts 32 and 33 of the con-
trol switch 26 and these contacts are respec-
30 tively connected by means of the wires 34
and 35 to two of the bus bars A as shown.
A suitable shunt wire 36 is connected to the
third bus bar A and the opposite terminal
35 of the shunt wire is connected to the sole-
noid 15, the opposite terminal of which is
connected to the wire 37 which in turn is
in electrical connection with the wire 28.
It is to be understood however that any
suitable wiring diagram may be used with-
40 out departing from the spirit and scope of
the invention as it is realized that varying
circumstances and conditions may require
more than the specific wiring diagram set
forth above. It is to be understood that
45 such changes as may be required to meet
the varying conditions may be made with-
out in any way departing from the spirit
and scope of the invention.

In the operation, it will be evident that
50 one of the generators is already in operation
and the current is passing over the bus bars
A and a second generator is to be cut in
and run parallel with the first mentioned
generator, the control switch 26 is closed so
55 that the current passing over to the bus bars A
will pass through the wire 35 into the contact
33, thence through the blade 31 into the
contact 27 and back through the wire 28, through
the wire 37 in the solenoid 15
60 and the current then passes through the
wire 36 of the opposite bus bar A. It will
also be noted that simultaneous with the
closing of the switch 26 the contact a of the
synchro-
scope 1 will be charged. It will also
65 be noted that the contact b of the synchro-

scope will be charged as the said contact is
connected with the second bus bar A by
the means of the wire 29, solenoid 22, wire
24, contact 25, blade 30, contact 32 and wire
34. The synchro-
scope is connected in the ordinary way so that the hand 3 carried thereby will indicate whether or not the generator which is being "run up" is in phase. When the hand stands vertical it is understood that the generators are in phase
75 and the same are ready to be thrown into parallel by the manipulation of the main switch. The operation of the main switch is controlled by means of the solenoid 22 and this solenoid is energized when the bridging contact 4 engages the contacts a—b so that the current flows from one of the bus bars A into the wire 35, thence through the control switch 26 into the wire 28, thence to the contact a, through the contact 4 and into the contact b, from whence the current passes into the wire 29 and solenoid 22 through the wire 24 and the control switch 26 into the wire 34, thus energizing the solenoid and causing the main switch 90 to close throwing in the second generator. The solenoid 15 which is shunted causing the first and second bus bar of the bars A is also energized so as to pull the arm 7 outwardly and cause the contacts 11 previously referred to in the wiring diagram as a—b to move into such position as to be engaged by the bridging contact 4. Owing to the fact that the contacts 11 are eccentrically mounted with relation to the shaft 2, it will 100 be seen that current cannot pass into the main switch solenoid 22 unless the hand stands in a vertical position.

While in the foregoing there has been shown and described the preferred embodiment of this invention, it is to be understood that such changes may be made in the combination and arrangement of parts as will fall within the spirit and scope of the appended claims.

What is claimed is:—

1. In a synchro-
scope, a dial, a hand movable over the face of the dial, a bridging contact carried by said hand, an arm pivoted to the side of the synchro-
scope, a ring centrally of the arm, a pair of contacts arranged at diametrically opposite points on said ring and in such a position that when the hand indicates synchronism the bridging contact will bridge the diametrically arranged contacts and a solenoid for moving the diametrically arranged contacts into engagement with the bridging contact when the device is set in operation.

2. The combination with a synchro-
scope having a movable bridging contact and fixed contacts co-operating therewith normally out of the path of the bridging contact, of magnetic means for moving the latter contacts into said path, a source of cur-

rent and a controlling switch for energizing said magnetic means, a main switch and connections establishing a circuit comprising the source, the fixed contacts, the main switch and the controlling switch.

3. A synchroscope comprising a casing, a dial on said casing, an arm pivoted to the side of the casing and extending across the face of the dial, a ring centrally of the arm, 10 a pair of diametrically opposed contacts on said ring, a link pivoted to the free end of the arm, a solenoid operating on said link to swing the arm on its pivot, said solenoid

tending to move the arm away from the dial, a hand movable over the face of the dial and bridging contacts on the hand adapted to engage the first mentioned contacts when the hand indicates synchronism and when the solenoid is energized.

In testimony whereof I affix my signature 20 in presence of two witnesses.
